UNITED STATES PATENT OFFICE.

ROBERT A. STEVENSON, OF LANCASTER, OHIO.

TOY CALCULATOR.

Application filed February 6, 1922. Serial No. 534,341.

To all whom it may concern:

Be it known that I, ROBERT A. STEVENSON, a citizen of the United States, and a resident of Lancaster, in the county of Fairfield and State of Ohio, have invented a new and Improved Toy Calculator, of which the following is a description, reference being had to the accompanying drawings, which are a part of this specification.

10 This invention relates to improvements in toy calculators wherein a number wheel is revolved for the purpose of making arithmetical calculations.

15 The object of my invention is to provide a device which, by musing children and arousing their interest, will help in teaching the principles of arithmetic.

20 More particularly, I seek to produce a toy device of this character which may be used for adding, multiplying, subtracting or dividing and which at the same time will be so simple in construction that a child will be able to understand its operation.

25 A further object is to make a toy calculator which having no intricate or delicate parts may be subjected to rough handling and not be easily broken.

30 My invention is shown in the accompanying drawings in which similar numerals indicate similar parts.

Figure 1 is a front elevation of the toy calculator as it would appear held before the operator.

35 Figure 2 is a cross-section on the line 2—2 of Figure 1 looking in the direction pointed by the arrows.

Figure 3 is an elevation of the supporting member.

40 Figure 4 is an elevation of the number wheel.

Referring first to Figures 1, 2 and 3, the supporting member 5 is provided with a slot 6 serving as a result slot. A pair of curved portions are provided on opposite sides of the supporting member 5, as indicated in Figures 1 and 3, and numerals from 1 to 10 inclusive are arranged in a circling manner upon these curved portions. The supporting member 5 is further provided with edge portions 7, 8, which act as finger stops. Near these finger stops I have placed the legend Stop, as indicated in Figures 1 and 3.

45 A journal pin 9 extends through the supporting member 5. Mounted upon this journal pin is a number wheel 10 provided

as shown in Figure 4 with a row of numerals which in this particular instance run from 0 to 48 inclusive. This wheel is provided with teeth 11 which extend beyond the curved portions on the sides of the supporting member. By aid of these teeth and the V-notches between the teeth the operator may turn the wheel in either of two directions. Each of the teeth 11 on the wheel 10 is in spaced relation to each of the numerals upon the oppositely disposed curved portions of the supporting member 5. Each of the numerals on the wheel 10 is so placed as to be registered one at a time through the slot 6 as the wheel is turned.

Two narrow slots 12 and 13 are cut in the supporting member 5, as shown in Figures 1, 2 and 3. A circle 14 is made upon the wheel 10 so that its center does not coincide with the center of the wheel but so that portions of it are always visible through the slots 12, 13. Thus, it will be seen that by turning the wheel 10 in either direction the circle changes its position in relation to the slots 12, 13, and gives the appearance of eyeballs rolling back and forth in the slots.

50 In describing the method of using the device for making calculations I will first explain how it may be used for adding or multiplying. The device is turned into such position that the supporting member 5 faces the operator as indicated in Figure 1. If it happens that the result slot 6 indicates a result previously found, the operator first

55 desires to clear the slot so as to cause it to register 0. In order to do this he places his finger in a notch between two of the teeth 11 and turns the wheel 10 in either direction until a single 0 is registered in the result slot. This leaves the device ready for either

60 adding or multiplying. According to Figure 1, the right-hand side of the calculator is used by the operator for addition and multiplication. For example, to add together 4, 8 and 7, he places his finger in the V-notch opposite the numeral 4 and rotates the wheel until his finger arrives at the legend Stop.

65 Next, leaving the wheel 10 in the position he now finds it he goes back and places his finger opposite the numeral 8 and turns the wheel as before until his finger reaches the legend Stop. Then he places his finger opposite the numeral 7 and makes a movement of the wheel until his finger again arrives at the legend Stop. This done, the slot 6 will 70 display the numeral 19.

In order to multiply, for instance, 9 by 3, the device is first cleared as described above so that the slot 6 displays the 0. The operator then places his finger opposite the 5 numeral 9 upon the right-hand side of the supporting member and pulls the wheel 10 in a clockwise direction until his finger arrives at the legend Stop. Repeating this 10 three times he essentially multiplies 9 by 3 so that the slot 6 will indicate a result of 27.

To use the device for subtracting or dividing, the operator uses the left-hand side of the calculator. For example, to subtract 9 from 42, the number wheel is turned in 15 either direction until the numeral 42 is made to appear in the slot 6. This done, the operator places his finger in the V-notch opposite the numeral 9 upon the left-hand side of the device and pulls down to the legend 20 Stop, thus turning the wheel 10 in a counter-clockwise direction. The number 33 now appears in the slot.

To divide, the number to be divided is first made to appear in the slot. For example, to divide 39 by 8, the wheel is turned so that 39 is registered in the slot. The finger is placed opposite the numeral 8 upon the left-hand side of the calculator and pulled down to Stop. This operation is 30 repeated, each time going back and placing the finger opposite 8. The operator mentally counts the times which this operation can be made before a numeral smaller than the divisor, in this case 8, appears in the 35 slot. In this example, when he has pulled down four times the numeral 7 will appear, therefore he makes no more operations as he has the correct result—4 with a remainder of 7.

40 It will be seen during the above calculations that the combination of the circle 14 with the slots 12, 13 will produce the effect of eyeballs moving back and forth, thus amusing the child that is operating the 45 device.

It is possible for a number of children, each provided with one of these calculators,

to make up games and contests to see which one can add, subtract and divide a series of numbers the quickest, which can be the most 50 accurate, etc, etc.

I am aware that calculators of this character have been patented which may be used for addition or multiplication but my improvement consists, principally, in providing 55 the means whereby the device may be used, also for subtraction and division.

Therefore, what I claim as my invention, is—

1. In a device for teaching arithmetic to 60 children having a supporting base plate provided with a result slot, a group of numerals adjacent to one edge thereof, and a rotatable number wheel carried by the base plate containing an annular row of numerals 65 arranged in consecutive order adapted to appear one at a time in rear of said result slot, means for attracting the attention of children to said device consisting of an annular design on said number wheel in eccentric relation to the axis thereof, said supporting face plate having a pair of diametrically aligned elongated openings disposed therein arranged at equal distances from the pivot point of said number wheel 70 through which the circular design is 75 adapted to appear.

2. In a device for teaching arithmetic to children, a supporting base plate shaped to simulate the appearance of a head of a figure and having a pair of elongated openings formed therein defining eyes, a dial disposed in rear of the face plate, a pivot for the dial carried by the face plate and an eccentrically disposed circular design disposed on the dial adapted to appear in rear of said openings, the dial and face plate having cooperating calculating means disposed thereon.

ROBERT A. STEVENSON.
